UNITED STATES PATENT OFFICE.

RAPHAEL SCHWEERS, OF BERLIN, GERMANY.

COPYING-MACHINE.

No. 835,561.

Specification of Letters Patent.

Patented Nov. 13, 1906.

Application filed August 12, 1905. Serial No. 273,897.

To all whom it may concern:

Be it known that I, RAPHAEL SCHWEERS, a subject of the German Emperor, residing at Berlin, Germany, have invented certain new and useful Improvements in Copying-Machines, of which the following is a specification.

This invention relates to letter-copying machines, and comprises improvements for feeding the letters to be copied to the copying-rollers, guiding the letters, timing their entrance between the copying-rollers, and receiving the cut copies from the web.

Four forms of construction are illustrated in the annexed drawings.

Figure 1 illustrates in vertical section a machine having a horizontal feed-table, an automatic feed-roller, and an adjusting and stop plate, and a receiver for the cut copies at the end of the machine opposite to the feed-table. Fig. 2 illustrates in a similar manner a machine having an inclined feed-table and an adjusting-plate. Fig. 3 illustrates in a similar manner a machine having the same parts as described with regard to Fig. 1, but differently arranged. Fig. 4 illustrates also in vertical section a machine in which the feed-table is at the same end of the machine as the receiver for cut copies.

The machine-frame, cutting device, copying-cylinders, water-receptacle, and various other parts are similar to the corresponding parts described in the specification of my former United States patent, No. 770,321, dated September 20, 1904.

The advantage secured by the automatic adjustment and feed of the letters between the copying-cylinders arises from the fact that it renders it unnecessary for the operator to pay special attention to inserting the letters into the machine in such a manner that each letter to be copied reaches the copying-cylinders at the moment at which the last letter copied leaves the said cylinders. The automatic adjustment allows of inserting the subsequent letter after a much briefer interval, and sufficient time is thus made available to insert the letters without stopping the machine. This is more particularly of importance in the case of copying-machines in which the copies are automatically cut from the web.

In all the constructions illustrated 8 is a roll of copying-paper, the web 9 of which passes under the roller 53 in the water-receptacle 54 and travels to the squeezing-rollers

1 and 2, which it reaches after passing a roller 52, by which the wet web is smoothed in order that it may pass between the rollers 1 and 2 without creases.

After passing between the rollers 1 and 2 the web 9 passes between the rollers 2 and 3, where the copying takes place, and is then fed by the rollers 4 and 5 to the knives 15 and 16. The end of the paper, with the copy thereon, hangs in front of the bow 13, which is rotatable about the axle 14. Shortly before the cutting operation begins the bow 13 is moved into the position shown in full lines in Fig. 1 and presses the copy 10 to be cut off against the fixed bar 17. The upper part of the copy cut off falls back over the bow 13, over which the copy remains suspended, whereupon the bow 13 returns to its original position and allows the next copy to pass between it and the bar 17, whereupon the operation is repeated.

20 is the table on which the letter to be copied is placed.

In each form of construction illustrated 6 is the oscillatory feed device which automatically inserts the letter between the copying-rollers. The oscillatory movement of this device is produced periodically. When the feed device 6 has been raised, the letter next 25 to be copied can immediately be placed thereunder and adjusted with its forward edge against the guide and stop-plate 18, Figs. 1, 3, or 4, or against the copying-roller itself, Fig. 2. The automatic insertion of the letter into the machine begins from this predetermined position.

The diameter of the copying-roller 2 is so proportioned to the length of the letter-paper that at the same moment at which the previous letter 22 passes from between the rollers the roller 6 descends and moves the next letter 21 between the copying-rollers immediately behind the letter 22.

To secure the action of the inserting device at the desired moment, the diameter of the roller 2 is preferably so calculated that it makes one revolution during the copying of a letter. If a cam, such as 41, is properly adjusted on the axle of the roller 2, with a ridge 42 of the proper length in contact with a projection 44 on the frame 19 of the inserting device, the latter is opened at the proper moment during the copying of a letter for the insertion of the following letter and closes at the proper movement by gravity for the purpose of inserting the latter.

The plate 18 may not only act as a stop-plate against which the forward edge of the inserted letter abuts when the letter is inserted, as in Figs. 1, 3, and 4, but it also acts as a guide-plate upon the movement of the feed device from its open to its feeding position. Ceasing then to act as a stop-plate it forms a directing-plate by which the edge of the letter fed forward by the feed-roller is deflected between the copying-rollers. In Figs. 1, 3, and 4 the plate 18 is hinged to the rocking frame 19, which carries the feed device 6. It rests loosely in Fig. 1 on roller 2, in Fig. 3 on table 20, and in Fig. 4 on roller 3. As the frame 19 moves up and down the plate 18 follows the contour of the roller or table on which its lower and outer end rests. In Fig. 2 the plate 18 is fixed to the frame 19; but it also in following the movement of the frame 19 moves athwart the plane of the table 20, and so deflects the letter when it is to be fed between the rollers 2 and 3.

The various parts of the machine are driven by a hand-crank 43 on shaft 44. This drives the roller 2 by pulley-strap 45. Rollers 1 and 3 are driven by friction from roller 2. Roller 6 revolves by friction when it falls into contact with roller 2, Fig. 1, or with roller 3, Figs. 2 and 4, or with a special roller 40, Fig. 3. Roller 40 is driven by pulley-strap 46. Roller 4 is driven by pulley-straps 47. Roller 5 revolves by friction with roller 4. The knife 15 is moved by hand-lever 33 and link 32. (See Fig. 3.) The bow 13 is rocked in one direction by cord 34, attached at one end to lever 33 and at the other to the bow 13 and passing round a pulley 35, and in the other direction by a spring 36.

What I claim as my invention, and desire to secure by Letters Patent of the United States, is—

1. In a copying-machine the combination with a plurality of copying-rollers, a displaceable feed device comprising a roller and a plate, and means connected with the copying-rollers for bringing said feed device into action and moving said plate at an interval equivalent to a predetermined distance of revolution of the copying-rollers and for moving said feed device out of action and restoring said plate to its previous position after a shorter interval.

2. In a copying-machine the combination with a plurality of copying-rollers, of a displaceable feed device comprising a roller and a gravity-operated stop-plate, and means connected with the copying-rollers for bringing said feed device into action and moving

said stop-plate so as to form a guide at an interval equivalent to a predetermined distance of revolution of the copying-rollers and for moving said feed device out of action and restoring said stop-plate to its stopping position after a shorter interval.

3. In a copying-machine the combination with a plurality of copying-rollers of a displaceable feed device comprising a movable plate and means connected with the copying-rollers for bringing said feed device into action and moving said plate to serve as a guide at an interval equivalent to a predetermined distance of revolution of the copying-rollers and for moving said feed device out of action and restoring said plate to stopping position after a shorter interval.

4. In a copying-machine the combination with a plurality of copying-rollers of an intermittently-operatable feed-roller and an adjusting device intermediate between said feed-roller and copying-roller and adapted to operate as a letter-stop when the feed-roller is out of operation and as a letter-guide when the feed-roller is in operation.

5. In a copying-machine the combination with a plurality of copying-rollers, a web-roller, a water-trough, a pair of cutters, an oscillatory receiving-bow for the cut copies, and means connected with the cutters for operating said bow.

6. In a copying-machine the combination with a plurality of copying-rollers, a web-roller, a water-trough, a pair of cutters, an oscillatory receiving-bow for the cut copies, means connected with the cutters for operating said bow, a displaceable feed device comprising a roller and a gravity-operated stop-plate and means connected with the copying-rollers for bringing said feed device into action and moving said stop-plate at an interval equivalent to a predetermined distance of revolution of the copying-rollers and for moving said feed device out of action and restoring said stop-plate after a shorter interval.

7. In a copying-machine, the combination, with a plurality of copying-rollers, of a guide-plate positioned with regard to said rollers so that a letter to be copied resting on said plate abuts on one of the copying-rollers, and means for displacing said guide-plate to deflect the letter between the copying-rollers.

In witness whereof I have signed this specification in the presence of two witnesses.

RAPHAEL SCHWEERS.
